UNITED STATES PATENT OFFICE.

WILLIAM H. SLATTEN, OF CHICAGO, ILLINOIS.

CAR ROOF.

Application filed February 19, 1921, Serial No. 446,253. Renewed February 23, 1922. Serial No. 538,704.

To all whom it may concern:

Be it known that I, WILLIAM H. SLATTEN, a citizen of the United States of America, and a resident of Chicago, in the county of

5 Cook, State of Illinois, have invented certain new and useful Improvements in Car Roofs, of which the following is a specification.

This invention relates to metal clad car 10 roofs of the type which constitutes the subject matter of Letters Patent No. 1,323,638, issued to me March 2, 1920, and this improvement has for its object:—

To provide a structural formation and 15 combination of the sectional members composing the outer sheet metal covering of the car roof, adapted to provide an approximately level nature to the exposed surface of the covering and prevent leakage of rain, 20 etc., to the car interior at the juncture points of the sectional members, all as will hereinafter more fully appear.

In the accompanying drawing:—

Fig. 1, is a transverse section, line 1—1 25 Fig. 3 of a car roof embodying the invention.

Fig. 2, is an enlarged detail section on line 2—2 Fig. 3 showing the construction at the eave portion of the roof.

30 Fig. 3, is an enlarged detail longitudinal section on line 3—3 Fig. 1.

Fig. 4, is a similar view on line 4—4 Fig. 1.

Like reference numerals indicate like 35 parts in the several views.

Referring to the drawing, 1 designates the usual side rails or plates connected by transverse carlines 2, and carrying the eave rails or fascia boards 3, the ridge pole 4, the pur- 40 lins 5 and the wood sheeting or sub-roof 6, with the parts having the usual arrangement and connection in general use in railway freight cars roofs.

7 designates a plurality of sheet metal por- 45 tions or members, which in connection with a plurality of intermediate channel plates 8 constitute the outer roof covering which overlies the sub-roof 6 above referred to, said portions being preferably of the sectional 50 central and twin side plate formation described in detail in Letters Patent aforesaid.

In the present construction the channel plates 8 occupy transverse gaps in the sub-roof 6, with the upper ends of the vertical 55 upturned webs of the channel plates disposed on a plane approximately the same

as that of the upper surface of the sheet metal portions 7. The connection between the parts 7 and 8 in a water and weather tight manner is effected by a construction 60 as follows.

9 designates downturned right-angle flanges on the respective sides of the sheet metal portions 7 and adapted for bearing contact against the respective inner faces of 65 the upturned webs of the channel plates 8, as shown more particularly in Fig. 3.

10 designates upturned flanges forming vertical and integral extensions of the aforesaid flanges 9 and arranged in spaced relation therewith so as to form narrow channels 70 for the reception of the downturned flanges of the cap pieces now to be described.

11 designates cap pieces of a channel shape in cross-section and having downturned 75 right angle flanges at the sides adapted to enter and fit the above described channels formed by the spaced flanges 9 and 10 of the sheet metal portions 7, with the top webs of the cap pieces on a plane approximately 80 even with that of the portions 7 and with said top webs resting upon the upper ends of the flanges 10 as shown.

12 designates downturned flanges on the outer ends of the cap piece 11 for attachment 85 to the fascia boards 3, and formed with ori- fices 13 adapted to register with the cavities of the channel plates 9 to permit a free outflow of any water which may enter into 90 said cavities.

In the present construction the respective ends of the cap pieces 11 will end at and engage the sides of the saddle blocks 14 of the running board 15 of the car roof, and the sheet metal portions 7 adjacent to said saddle 95 blocks will have their flanges 10 removed and their flanges 9 formed to fit the metal confining plates 16 of the aforesaid saddle blocks as shown in Fig. 4.

The present construction is adapted to 100 meet in an effective and economical manner, the requirement of flexibility in the roof corresponding with the flexibility of the car body structure and at the same time afford a rain tight connection between the sections 105 and parts comprising the metal roof covering.

Having thus fully described my invention what I claim as new and desire to secure by Letters Patent, is:—

110 1. In a car roof, the combination of a plurality of transversely arranged channel mem-

bers disposed in gaps of the sub-roof and having upstanding flanges, a plurality of transversely extending sheet metal sections having downturned marginal flanges adapted to contact with the upstanding flanges of the channel members, said downturned flanges having vertical extension flanges in spaced relation to provide narrow receiving channels, and cap pieces of a channel shape and having downturned flanges adapted to fit the channels formed by the aforesaid flanges.

2. In a car roof, the combination of a plurality of transversely arranged channel members disposed in gaps of the sub-roof and having upstanding flanges, a plurality of transversely extending sheet metal sec-

tions having downturned marginal flanges adapted to contact with the upstanding flanges of the channel members, said downturned flanges having vertical extension flanges in spaced relation to provide narrow receiving channels, and cap pieces of a channel shape and having down-turned flanges adapted to fit the channels formed by the aforesaid flanges, said cap pieces having at their outer ends downturned attaching flanges formed with orifices adapted to register with the cavities of the channel members aforesaid.

Signed at Chicago, Illinois, this 17th day of February, 1921.

WILLIAM H. SLATTEN.
